INVENTOR

John L. Shaw
BY Edward Tazzart

His ATTORNEY

UNITED STATES PATENT OFFICE.

JOHN L. SHAW, OF GRAND RAPIDS, MICHIGAN.

MACHINE FOR AFFIXING POSTAGE-STAMPS.

SPECIFICATION forming part of Letters Patent No. 337,450, dated March 9, 1886.

Application filed May 27, 1884. Serial No. 132,968. (No model.)

To all whom it may concern:

Be it known that I, JOHN L. SHAW, a citizen of the United States, residing at the city of Grand Rapids, in the county of Kent and State of Michigan, have invented a new and useful Machine for Affixing Postage and other Stamps, of which the following is a specification.

My invention relates to the use of a water-reservoir with a hand-stamp for attaching stamps to paper or other material; and its objects are, first, to moisten the stamp or paper by a spray from the water-chamber; second, to press the stamp upon the paper by the same movement of the hand that throws the spray; third, to support the stamps in a chamber so that but one stamp can escape at a time and only when the paper is in position to receive the stamp; and, fourth, to combine the whole in a small compact machine suitable for desk and office use. I attain these objects by the mechanism illustrated in the accompanying drawings, in which—

Figure 1 is a side elevation of my stamp-affixing machine. Fig. 2 is a front elevation of the same. Fig. 3 is also a front elevation of the same with the hand-pieces primed down, showing the position of the machine at the instant the stamp is affixed to the paper. Fig. 4 is a vertical sectional view of the air-cylinder G and parts attached thereto.

Similar letters refer to similar parts throughout the several views.

The general form of my device does not differ from ordinary hand-stamps. It has a base of metal or any suitable material, which I have shown as circular in the drawings. It has a support, L, which supports the stamp proper. A is a hand-plate attached to the upper end of the piston-rod C and rod D. The rod C passes through the plate B into the air-chamber G, and is attached to the piston 15 in the air-chamber, which air-chamber extends downward, as shown by dotted lines in Fig. 1, and has an opening into tube 5. At the top of the air-chamber is a small air-vent, a.

Beneath the piston at the bottom of air-chamber G is a spring, 14, (shown in Fig. 4,) which brings A and C to the position shown in Fig. 1 as soon as the pressure on A shall have been removed.

6 is an elastic air-tube connected to short tube 5, and it has an aperture, 8.

N is a reservoir for water, which reservoir fits into the shell K, the two combined forming a reservoir similar to the oil-reservoir in an ordinary student-lamp, the construction of which is well known. My object in adopting this construction is to keep the water in K at the same level at all times, it being supplied from the part N as it is used out in operating the machine.

X is a tube opening into the reservoir K, and provided with an aperture, 9.

At the bottom of cylinder G, and attached thereto by means of the metallic band P, is the follower J.

H is a head-block, rigidly attached to the support L, and it has an opening through it which allows the cylinder G to move freely up and down through such block.

E is a coiled spring, to bring B into place when the pressure has been removed.

Attached to the band P are two spring-catches, 1 and 3, which are held in locking position on pin 1' by springs 2 and 4.

F is a wedge-shaped lug on the rod D. By pressing down on hand-plate A the rod D passes between catches 1 and 3, and when A is brought in contact with B the wedge-lug F separates the catches 1 and 3, so as to disconnect the catches from the pin 1', as shown in Fig. 3. The follower J being disconnected from the head-block H, the pressure upon A now presses the cylinder G downward until the follower J comes in contact with the pad 10 on block 11.

M is the stamp-holder, which is made, preferably, of thin metal, and fits onto the follower J by spring-catch, or otherwise, but so as to allow the follower to slide therein. This connection is shown in the drawings as a spring, j', which at the lower end is connected to the stamp-holder by rivet y, and to the follower by a screw, y², in the band P on the follower. On the lower back side of this holder is a drip or water table, 7, designed to prevent the water from dripping onto the cushion 10.

On the block 11 are two guides, 12 and 13, for keeping the letter or paper in proper position to receive the stamp.

The operation of my invention is as follows:

Place the letter on the cushion 10 and press downward on plate A. The piston passing downward within the cylinder G drives the air into the tube 6 and out of the opening 8. 5 This causes a suction through the tube X, and the water escaping through aperture is atomized, and will cover a space on the letter of the size of a single stamp. When the plate A has reached the plate B, the lug F has disconnected the follower J from the head-block H, and the plate B descends with the combination of the same stroke, driving before it cylinder G and follower J, bringing the lower stamp on the holder M upon the moistened 10 surface of the letter, to which it adheres, and the pressure being removed the machine immediately assumes the position shown in Fig. 1.

Instead of throwing the spray downward upon the envelope, it may be turned upward, 15 so as to moisten the lower or adhesive face of the stamp; but I deem the method first above described preferable.

Having thus described my invention, what I claim to have invented, and desire to secure 20 by Letters Patent, is—

1. A stamp-affixing apparatus provided with an air-reservoir and piston, in combination with a water-reservoir and spraying device, and suitable connecting air and water tubes, 25 substantially as described.

2. A stamp-affixing device provided with a water-reservoir and spraying device, substantially as and for the purpose described.

3. In a stamp-affixing apparatus, a pressure-plate, a piston to which said plate is attached, 35 a spring for returning the piston to its normal position, and an air-cylinder within which the piston operates, the said cylinder provided with an air-vent and air-tube for the ingress and egress of air, in combination with a water-reservoir provided with a tube extending 40 therefrom, having an opening near that of the air-tube, whereby spray is emitted when pressure is exerted on said presser-plate, substantially as and for the purpose described. 45

4. In a stamp-affixing apparatus, a presser-plate, a piston to which said plate is attached, a vertically-reciprocating cylinder, a spring within said cylinder beneath the piston, a follower attached to said cylinder, and a stamp-holder attached to said follower, and a water-vessel, substantially as and for the purpose described. 50

5. A stamp-affixing apparatus comprising, in combination, the pressure-plates, the piston, the air-cylinder, the springs, the follower, the stamp-holder, the base-block and cushion, the water-reservoir N K and their connecting air and water tubes, and a spraying device, substantially as and for the purpose described. 55 60

JOHN L. SHAW.
